UNITED STATES PATENT OFFICE.

SOLOMON GERMAN, OF UNIONVILLE, MARYLAND.

CORN-HUSKING MACHINE.

1,047,783.

Specification of Letters Patent. Patented Dec. 17, 1912.

Application filed February 20, 1912. Serial No. 678,859.

To all whom it may concern:

Be it known that I, SOLOMON GERMAN, a citizen of the United States, residing at Unionville in the county of Frederick and 5 State of Maryland, have invented certain new and useful Improvements in Corn-Husking Machines, of which the following is a specification.

This invention relates to corn-husking 10 machines and has for its object to provide a machine of this class which will be strong, simple and economical in construction, efficient and reliable in operation, not liable to get out of order in ordinary use, and easy 15 to repair when necessary.

With this idea in view the invention consists in the improved construction, arrangement and combination of the parts of a corn-husker which will be hereinafter fully 20 described and afterward specifically claimed.

In order that the construction and operation of the invention may be readily comprehended, I will now proceed to specifically describe a preferred embodiment of 25 it as illustrated in the accompanying drawings in which—

Figure 1 represents a plan view with a part of the fan and casing broken away and other parts shown in dotted lines, Fig. 2 30 represents a view partly in longitudinal vertical section and partly in side elevation, Fig. 3 represents a transverse vertical sectional view taken on the plane indicated by the broken line 3—3 of Fig. 1, looking toward the right as indicated by the arrows, and Fig. 4 represents a similar view taken 35 on the plane indicated by the broken line 4—4 of Fig. 1, looking to the left as indicated by the arrows, parts being broken 40 away.

Like reference characters mark the same parts in all of the figures of the drawings.

My improved machine may be made stationary but I prefer to make it portable and 45 for this purpose I support the whole structure upon a frame work comprising longitudinal beams 10 and 11 supported on cross beams 12 and 13, mounted on axles 14 and 15 carrying front wheels 16 and rear wheels 50 17, forming a wagon or vehicle of ordinary construction and provided with a suitable fifth wheel 18 and tongue 19, whereby it may be hauled from place to place.

Upon the longitudinal beams 10 and 11 is 55 supported a platform 20 upon one side of which is mounted a longitudinal boxed in

frame 21, and at the top of each side of which is a beam 22 forming tracks upon which are mounted the wheels 23 of a car or truck 24 in the body of which is carried the 60 corn to be husked whereby the supply of material may be moved longitudinally with relation to the operating mechanism to be hereinafter described.

The mechanism of my invention may be 65 driven by any suitable engine or motor and I have illustrated a gas engine 25 for the purpose mounted on the platform 20, which engine may be of any preferred type provided with a shaft 26 with the usual fly 70 wheels 27 mounted thereon, the particular motor or engine being a matter of choice and forming no part of the invention. The shaft 26 carries a pulley 28 connected by a belt 29 with a pulley 30 on a shaft 31 mounted in suitable bearings 32 on a cross beam 33 connecting vertical posts 34 rising from the platform 20, cross beams 36 which connect these posts at their upper ends, serving to support a table 37 for purposes hereinafter to be described. On the shaft 31 is 75 a pulley 38 connected by a belt 39 with a pulley 40 on a shaft 41 journaled in bearings 42 mounted on the table 37 upon the inner end of which shaft 41 is fixed a circular knife 43 having on its inner face at the center thereof, a spiral knife or blade 44, the circular knife projecting through a slot 80 45 in the table 37.

In the table adjacent to the spiral and 90 circular knives is an opening 46 and from the bottom of the table at the edges of said opening depends suitable supports (comprising bolts 47 on which are sleeves 48) for a bar 49 in which are mounted slidable uprights 50 passing upward above the table through the opening 46 and carrying a hand rest 51 at their upper ends, a spring 52 surrounding each upright 50 and bearing at its end against the bar 49 and hand rest 51 100 whereby the latter is yieldingly supported in its highest position, in front of the spiral knife 44.

In the table 37 at a short distance from the knives, is a hopper 53 having a cylindrical spout 54 below the table from which spout depend a plurality of yielding arms 55 inclined toward each other at their lower ends and provided with inwardly projecting knobs or pegs 56, said arms assuming normally the form of a skeleton inverted truncated cone from which one or more arms are 105 110

lacking on one side, said arms being opposite a disk 57 provided with like knobs or pegs 58 and fixed on a short counter shaft 59 journaled in bearings 60 depending from the under side of the table 37. This counter shaft 59 carries a pulley 61 connected by a belt 62 with a pulley 63 on the shaft 31.

Beneath the table 37 and inclosing that part of the circular knife 43 which projects below the table is a trough 64 having one end outside of said knife, as at 65, closed, and inclined downward toward and discharging through an opening 66 into a box 67 depending from the table and inclosing the knobbed arms 55 and disk 57 as well as one of the bearings 60 of the counter shaft 59, said shaft passing through one side of the box. From this box 67 extends laterally a spout 68 inclined downwardly and discharging into the box 21 on the track frame.

At the end of the box 67 opposite the spout 68, and at the lower end of the inclined bottom of the box is an opening 69 into which projects the discharge mouth 70 of a casing 71 which incloses a fan 72 mounted on a shaft 73 which carries a pulley 74 connected by a belt 75 with a pulley 76 on the shaft 31.

Bolted to the platform 20 is a shelf 77 upon the top of which are pivoted two links 78 which are pivotally connected at their upper ends to the under side of an inclined spout 79 below and inclined away from the discharge end of the box 67, said spout being perforated at 80 in its center portion for a short distance and connected at its upper ends to the outer end of a rod 81 projecting from bands 82 around an eccentric 83 on the shaft 31. Mounted below the perforated portion of the spout 79 is a hopper 84 supported in an opening in the shelf 77 and provided at its lower end with a cylindrical discharge spout 85 upon which is provided hooks 86 upon which to hang a bag or other receptacle 87 said spout being provided with a sliding valve 88.

The operation of my machine may be described as follows: The corn in the husks being contained in the truck body 24 it is passed to, or taken from the truck by, the operator standing upon the platform between the truck and the operating mechanism, who presents it, butt forward to the action of the circular knife 43, which cuts off the butt end and leaves the husk simply wrapped on the ear and unconnected at the butt. The ear thus prepared is rested upon the hand rest 51 and pressed down with said rest against the upward pressure of the springs 52 until the ear is centered with relation to the spiral blade 44 when it is pressed endwise against that knife which loosens up the ends of the husks and perfects the operation begun by the circular knife.

The ear, with the loosened husks upon it is passed downward through the hopper 53

between the bars 55, and comes in contact with the disk 57 on that side where a bar is missing. The rotation of the disk rotates the ear held between the bars 55 and strips the loosened husks off the cob, when the husks are blown by the fan through the spout 68 into the box 21. The stripped ears are fed down by the disk 57 upon the inclined bottom of the box 67 whence they pass out at 69 upon the shaking trough 79 from which they are discharged into any suitable receptacle. The grains of corn which have been shattered off the ears drop down and pass out at 69 upon the shaking trough 79 and pass through the perforations 80 into the bag 87, or other receptacle.

The construction and operation of my invention will be readily understood from the foregoing and it will be obvious to those skilled in the art to which my invention most nearly appertains that many changes and variations may be made in the construction of the various parts, and in the manner of connecting and operating them, without departing from the spirit and scope of the invention as defined in the appended claims.

Having thus described my invention, what I claim as new and desire to secure by Letters Patent of the United States is—

1. In a corn husker, a rotating circular cutter for severing the butts of the ears from the main body thereof and a knife secured thereon and arranged spirally around its axis for loosening the husks on the ears.

2. In a corn husker the combination of a circular rotary knife, a spiral blade centrally arranged on one side thereof and a vertically yielding hand rest in front of the spiral blade.

3. In a corn husker the combination of a table having an opening therein, a circular knife having on one side a spiral blade a bar supported below the opening in the table, and a yielding hand rest in front of the spiral knife and supported on said bar.

4. In a corn husker the combination of a table having an opening therethrough, a hopper above the table, a spout from the hopper projecting through, below the table, a series of yielding arms depending from the spout and provided with inwardly projecting knobs, and means for rotating an ear of corn between the bars.

5. In a corn husker the combination of a table having an opening therethrough, a hopper above the table, a spout from the hopper projecting through and below the table, a series of arms depending from the spout and provided with inwardly projecting knobs, said arms having an opening between them on one side thereof, a vertical disk having knobs on its face at the opening between the arms, and means for rotating the disk.

6. In a corn husker the combination of a

table having an opening therethrough, a hopper above the table, a spout from the hopper projecting through and below the table, a series of arms depending from the 5 spout and provided with inwardly projecting knobs, a vertical disk having knobs on its face positioned and adapted to rotate in an opening between the arms, a box having a discharge opening at each end and located

below the disk and arms, and a fan arranged 10 to discharge a current of air through the box toward one of the discharge openings.

In testimony whereof I affix my signature in presence of two witnesses.

SOLOMON GERMAN.
